(57) **CLAIM**

The ornamental design for a handbag, as shown and described.

DESCRIPTION

FIG. 1 is a front elevational view of a handbag showing a first embodiment of my new design.

FIG. 2 is a rear elevational view thereof.

FIG. 3 is a right side elevational view thereof.

FIG. 4 is a left side elevational view thereof.

FIG. 5 is a bottom plan view thereof.

FIG. 6 is a top plan view thereof.

FIG. 7 is a perspective view thereof.

FIG. 8 is a front elevational view of a handbag showing a third embodiment of my new design.

FIG. 9 is a rear elevational view thereof.

FIG. 10 is a right side elevational view thereof.

FIG. 11 is a left side elevational view thereof.

FIG. 12 is a bottom plan view thereof.

FIG. 13 is a top plan view thereof; and,

FIG. 14 is a perspective view thereof.

The broken lines showing stitching are for the purposes of illustrating environment and forms no part of the claimed design.
